UNITED STATES PATENT OFFICE

142,355

DESIGN FOR A FLATIRON

Don E. Stewart, Grand Rapids, Mich., assignor to
Raymond J. Scheffler, Grand Rapids, Mich.

Application July 20, 1944, Serial No. 114,485

Term of patent 14 years

(Cl. D49—6)

To all whom it may concern:

Be it known that I, Don E. Stewart, a citizen of the United States, residing at Grand Rapids, in the county of Kent and the State of Michigan, have invented a new, original, and ornamental Design for a Flat Iron, of which the following is a specification, reference being had to the accompanying drawing, forming part thereof.

Fig. 1 is a perspective view of a flatiron showing my new design.

Fig. 2 is a top plan view of the same, and
Fig. 3 is a side elevation of the same.

I claim:

The ornamental design for a flatiron, substantially as shown.

DON E. STEWART.
